CLAIM

The ornamental design for a steering wheel, as shown and described.

DESCRIPTION

FIG. 1 is a front view of the steering wheel and related structures showing my new design;

FIG. 2 is a back view thereof;

FIG. 3 is a left side view thereof;

FIG. 4 is a right side view thereof;

FIG. 5 is a top view thereof;

FIG. 6 is a bottom view thereof; and,

FIG. 7 is a perspective view thereof.

Features of the steering wheel shown in broken lines form no part of the claimed design.

1 Claim, 7 Drawing Sheets
